DESCRIPTION

FIG. 1 is a perspective view of a vehicle pedal locking device showing our new design, in use.

FIG. 2 is a side view thereof;

FIG. 3 is a side view thereof;

FIG. 4 is a front view thereof;

FIG. 5 is a back view thereof;

FIG. 6 is a top view thereof; and,

FIG. 7 is a bottom view thereof.

The broken lines shown in FIG. 1 represent unclaimed subject matter and form no part of the claimed design.
